UNITED STATES PATENT OFFICE.

THOMAS JARBOE, OF SAN FRANCISCO, CALIFORNIA.

HOT PLATE.

Application filed May 11, 1927. Serial No. 190,424.

This invention relates to improvements in hot plates and more particularly to supplementary hot plates for use in combination with gas stoves.

5 Among the objects of the invention are to conserve the heat generated by gas stove burners, whereby the maximum amount of heat may be applied to the cooking utensil with the minimum amount of gas consumption. A further object of the invention is to improve combustion by providing a regenerative chamber for the expansion, oxidation and complete combustion of the gases ignited beneath the hot plate. A further object is to uniformly distribute the heat generated beneath the cooking utensil for the purpose of applying a uniform temperature throughout the exposed area of the cooking utensil bottom, with the advantage that food 20 may be uniformly cooked as fast or as slowly as desired, without circumscribed areas or spots wherein the applied temperature is higher or lower than at other similar spots throughout the cooking area of the utensil. Other objects and advantages will appear as 25 this description progresses.

In this specification and the annexed drawings, the invention is illustrated in the form considered to be the best, but I do not wish to 30 be understood as confining it to this form, because it may be embodied in other forms, and it is also to be understood that in and by the claims following the description it is desired to cover the invention in whatsoever form it 35 may be embodied.

In the accompanying one sheet of drawings, Fig. 1 is a plan view from above of a hot plate constructed in accordance with this invention, the cover plate being partially 40 broken away to show the structure and relation of the regenerative plate beneath. Fig. 2 is a cross-section taken through the diameter of the same at II-II.

In detail the construction illustrated in the 45 drawings comprises a disc like plate 1, preferably circular in shape and composed of cast iron or other suitable stove material. This plate is provided with the integrally cast concentric flanges 2, 3 and 4. The first flange 50 2 is preferably located at the perimeter of the plate 1; the flange 4 is located at the center of the plate 1 and its diameter is approximately equal to one-third the diameter of the plate, and the flange 3 is interspaced between the flanges 2 and 4. These dimensions are 55 merely approximate and may be varied to

suit circumstances. Each of these concentric flanges is provided with a series of interspaced gaps 5. These gaps are placed in interspaced relation to each other in the several flanges mentioned, that is, the gaps are placed in radial alinement with each other, the gaps in the intermediate flange 3 being between the lines of the gaps in the flanges 2 and 4. These flanges project above the plane of the plate 1 any suitable distance, one-quarter of an inch being quite sufficient for the average size plate. The plate 1 is also provided with the lugs 6, spaced about the circumference of the plate 1, preferably between the gaps 5 in the flange 2. The plate is also provided with a central lug 7, having a center opening therethrough and countersunk on the lower side to receive the conical head of the stove bolt 8.

The cover comprises a circular disc of metal, preferably sheet aluminum 10. This cover has a depending flange 11 encircling the regenerative plate 1 and engaging the lugs 6. This plate has the radiating embossed ribs 12, radiating from the depressed center 13 and extending approximately to the flange 11. Six of such ribs are shown in the drawing, but three or more will serve the purpose hereinafter described. These ribs 12 divide the cover into segmental areas. The openings 14, through the cover, are located at the apices of these segmental divisions and are within the area confined by the flange 4 on the plate 1.

The cover 10 is assembled on the plate 1 by means of the stove bolt 8 passing therethrough and engaging the nut 9 screwed thereon, pulling the depressed center 13 of the cover snugly against the top of the lug 7. It is unnecessary to the functioning of this invention that these two parts be thus positively secured together, but it is convenient in handling the device, especially when it is hot. The regenerative plate 1 and the cover 10 will be held in their operative relation by the lugs 6 engaging the flange 11 to center the two parts, one upon the other.

This invention operates substantially as follows: The device is placed over the ordinary gas plate common to stoves using commercial gas or having flames generated from gasoline or kerosene, or other Bunsen type of flames. The flame impinging against the lower side of the plate 1 is spread thereby and curls upward into the regenerative chamber between the edge of the plate and the

flange 11 and is trapped between the lugs 6, before passing through the various gaps 5 in the flange 2. The flame passes into the concentric space between the flanges 2 and 3, 5 and the plate 1 and the cover 10, across which it travels towards the gaps 5 in the flange 3, through which it escapes into the space intermediate the flanges 3 and 4 until it escapes 10 through the gaps 5 in the flange 4, thence into the center space confined by the flange 4, from whence it escapes through the openings 14 into the various segmental areas of the cover 10 between the ribs 12. From thence it again 15 travels laterally beneath the bottom of any utensil resting upon the ribs 12, until it escapes upward beyond the circumference of the utensil. Since the ribs 12 rise above the plane of the cover 10 some of the products of combustion travel along beneath these ribs 20 from the flange 2 to the center space within the flange 4.

The effect of this device is substantially as follows: Cast iron is preferred for the regenerative plate 1 because of its well known absorption coefficient for heat, due very largely 25 to its porosity. This plate gradually becomes very hot, so that the products of combustion passing between it and the cover 10 along the tortuous route described, are subjected to a 30 certain expansive and regenerative effect which liberates the unconsumed carbon suspended in the products of combustion from the flame and is subjected to the oxidizing effect of the free air drawn in between the 35 edge of the plate 1 and the flange 11 by the natural aspirative effect of the flame and products of combustion travelling therethrough. The flames of hydro-carbon burners also carry a large percentage of moisture 40 which upon reheating and regeneration contributes to the improvement of combustion, adding to the liberated heat units. The circuitous route taken by the products of combustion in passing through the gaps between the various concentric areas between the 45 flanges 2, 3 and 4, delays its passage and permits the necessary interval for the heat units to be absorbed and equalized by the cover 10 and transmitted therefrom to the bottom of 50 the cooking utensil resting upon the ribs 12. The residual parts of combustion, passing through the openings 14, flow laterally immediately in contact with the bottom of the utensil, before escaping therefrom, after having given up most of their heat units to the 55 utensil.

Aluminum is preferred for the construction of the cover 10 because of its inherent

tendency to retain heat and therefore uniformly distribute it throughout its area. 60 This is amply demonstrated by the fact that food does not so readily burn in aluminum utensils; therefore the absorbent and radiating value of cast iron, with the distributing and retaining value of aluminum with respect to heat units, makes in this device a combination admirably suited to the purpose of conserving heat units by confining them to the area for direct application to the food or other substances to be subjected thereto; with the 65 additional regenerative effect of improved combustion which is desirable from the standpoint of economy.

It sometimes happens, where this device is used over flames that are not properly adjusted, that soot will accumulate within the regenerative chamber between the plate 1 and the cover 10. This may be easily removed by submerging the whole device in hot water 70 with suitable caustics and boiling the same or 80 by removing the nut and bolt, 8-9, separating the parts and dusting out the accumulated soot in the dry state.

Having thus described this invention what I claim and desire to secure by Letters Patent is:

1. A hot plate comprising a regenerative plate having a flat under surface; peripheral lugs extending beyond the edge of said plate; concentric segmental flanges extending above the top of said plate; a cover having openings in its center portion and a depending flange 90 engaging said lugs.

2. A hot plate comprising a regenerative plate having a flat imperforate under surface; a concentric segmental flange rising at the periphery and extending above the top of said plate; intermediate concentric flanges arranged on said plate within said peripheral flange; a cover resting upon said flanges having openings in its center portion and a depending flange extending beyond and spaced from the periphery of said plate.

3. A hot plate comprising a regenerative plate having a flat under surface; a concentric segmental flange rising at the periphery and extending above the top of said plate; a cover having openings near its center portion and resting upon said flange and having a flange extending beyond and below the periphery thereof; radial ribs on the top of said cover between the said openings.

In testimony whereof I have hereunto affixed my signature.

THOMAS JARBOE.
